UNITED STATES PATENT OFFICE.

HARRY L. RODERICK AND HARRY D. NEWHART, OF OROVILLE, CALIFORNIA; SAID NEWHART ASSIGNOR TO SAID RODERICK.

AIRSHIP.

1,175,474.

Specification of Letters Patent. Patented Mar. 14, 1916.

Application filed March 20, 1911. Serial No. 615,488.

To all whom it may concern:

Be it known that we, HARRY L. RODERICK and HARRY D. NEWHART, citizens of the United States, residing at Oroville, in the county of Butte and State of California, have invented new and useful Improvements in Airships, of which the following is a specification.

One object of the present invention is to provide an air ship having an arrangement of aeroplanes by which the air pressure may be utilized in the most efficient manner possible.

A further object is to provide one in which the pressure of the air developed by the propeller may be utilized both to elevate the ship and to maintain its balance.

A further object is to provide an auxiliary device, independent of said aeroplanes for automatically balancing laterally the air ship, against irregular wind action.

A further object is to provide means whereby said auxiliary device may also be used at the will of the operator as well as automatically.

In the accompanying drawings, Figure 1 is a side view of the air ship; Fig. 2 is a broken plan view of the same; Fig. 3 is a front view.

Our improved air ship is, in general, of the monoplane type, that is to say, it comprises an elongated frame 1, supported when at rest upon front wheels 2 and rear wheels 3 which are at a considerable distance from one another, and supporting at the rear end the lateral steering rudders 4, the stationary vertical plane 5 in the same vertical plane with the front edge of said lateral steering rudders, the elevating rudders 6, and the substantially horizontal planes 7 in the same general direction with the front edge of said vertical steering rudders. Supported upon the upper portion of the frame 1 near its front end are the front and rear cross bars 8, 9, of the main aeroplanes 10 of our improved air ship, said aeroplanes 10, or, as they may be termed, aeroplane sections, extending at the sides of the ship outside the main frame and being supported upon rods

11 of the usual form secured to said cross bars and extending rearwardly from the rear cross bar. 12 indicates the propeller, the shaft 13 of which is supported upon the top of the main frame at the front end

thereof, in a suitable bearing 14 upon the front cross bar, having a rear bearing on a cross support 15 extending between the upper members of the main frame said shaft having thereon a pulley 16 driven by a belt 17 from an engine 18 which is supported in the lower portion of the main frame at the front end thereof.

No novelty is claimed for the portion of the air ship heretofore described.

Great rearward air pressure is produced by the propeller, and heretofore this pressure has been utilized only to a small extent, the greater portion of the air under said pressure escaping in the central space between the two sections of the main aeroplane without producing any lifting effect. One object of our invention is to utilize this air pressure. For this purpose we provide an auxiliary aeroplane 20, which is supported upon posts 21, the lower ends of which rest upon the upper longitudinal members of the main frame. said aeroplane 20 being suitably connected by guy-wires 22. This auxiliary aeroplane is of the same depth as the main aeroplane and its front and rear edges are both set back slightly from those of the main aeroplane. It is however of considerably less width than the combined widths of the main aeroplane. The utility of this auxiliary aeroplane will appear from the following considerations. The propeller produces a rearward movement of air and in our invention this rapidly moving air impinges upon the under side of said auxiliary plane, and by reason of the concavity of said plane, produces thereon a lifting effect. It also produces a balancing effect. The air pressing upon the under side of this auxiliary plane arrives in three ways. Part of the air comes directly against said under side over the upper portions of the main planes, and is caused by the mere movement of the air ship through the air. This portion of the air pressure is the same at all points transversely of the air ship. A second portion of the air passes over the upper portion of the main plane sections but is produced by the rotary movement of the propeller. It is evident that this portion of the air pressure will be much the greatest in the central portion of the auxiliary plane. A third portion of the air pressure comes by way of the air passing beneath the main

aeroplane and forced thereunder by the propeller or by any other means and escaping past the inner ends of the sections of the main aeroplane up through the opening 5 between them. It is evident that this pressure is also by far the greatest in the center of the auxiliary aeroplane. From this it is apparent that the pressure in the center of the auxiliary aeroplane is much greater than 10 that at the ends, probably from two to three times as great, and therefore the auxiliary aeroplane thus arranged has a balancing effect as well as a lifting effect.

Upon the main frame at a distance to the 15 rear of said main aeroplane slightly less than the depth of the said aeroplane is supported by posts 25 a supplementary aeroplane. This is the same depth as the auxiliary aeroplane, but slightly shorter. It is 20 arranged at such a level that its downward and rearward slope is substantially a continuation of the downward and rearward slope of the auxiliary aeroplane. The object of the supplementary aeroplane is to utilize the pressure 25 of the air escaping from between the main and auxiliary aeroplanes. It is well known that a current of air which has been deflected by a plane, on passing the rear edge of said plane, has a tendency to curl, as it 30 were, in a wave motion around said rear edge, or to return to its former direction. This is due to the fact that the relative velocity of the air in immediate contact with said plane is reduced, while the velocity of 35 the air which is not in immediate contact therewith is not reduced, or, if reduced, the reduction is very little. On account of this difference in velocity between the air which is in contact with the plane and that which 40 is remote from the plane, the air in passing the rear edge of auxiliary plane acquires an upward direction. The supplementary aeroplane takes advantage of the pressure thus produced.

45 Another effect produced by said supplementary plane is to counteract the tendency of the air ship to rock in a longitudinal direction. Said supplementary plane causes the air ship to fly with exceeding smoothness 50 and uniformity of angular elevation.

We provide additional means for preserving the balance of the air ship, which means is used automatically, but may also be used at the will of the operator. This means comprises a vertical vane 30, secured at a point about one-fifth of its length from its front edge to the upper portion of a shaft 31. This shaft passes through suitably supported upper and lower bearings 32, 33. 55 From said shaft extends rigidly secured thereto a rearwardly and downwardly sloping arm 34, to the end of which is secured a weight 35. This device acts in the following manner. The pressure of the air against both sides of the vane tends to keep it par-

allel with the longitudinal direction of the air ship, and therefore also the arm carrying the weight normally extends directly rearward. But should the air ship tilt to one side, then the weight will also swing to that side 70 and in doing so it will rock the vertical shaft 31 so that the rear portion of the vane will swing to that side and present a large surface directly exposed to the action of the air through which the ship is moving, and thus operate partly as a lifting plane and partly as a steering plane to bring the ship to its vertical or normal position. Arms 37 also extend from the shaft in opposite directions, upon which the feet of the 80 operator, seated on a seat 38, can rest, so that, in case of emergency, he can with his feet, turn the shaft and thus move the rear portion of the vane to either side of the ship to produce the same effect as is produced automatically.

We claim:—

1. In an airship, a main transverse aeroplane comprising two aeroplane sections spaced apart centrally, their rear edges being lower than their front edges to increase the pressure of the air passing thereunder beneath said front edges, said sections being so inclined transversely that air having its pressure so increased escapes past their inner ends into said central space, and an auxiliary rectangular aeroplane having its front edge in the rear of the front edge of the main aeroplane, and its rear edge in the rear of the rear edge of the main aeroplane 100 and at a distance therefrom less than the depth of the main aeroplane and at a higher level, extending over said central space and over the inner ends of the main aeroplane sections to receive the upward pressure from the air escaping into said central space from said main aeroplane, and likewise having its rear edge lower than the front edge.

2. In an air ship, the combination of a propeller having a horizontal shaft, a main transverse aeroplane substantially in the plane of the shaft of the propeller and comprising two aeroplane sections spaced apart centrally, an auxiliary aeroplane of considerably less width than the main aeroplane and at a higher level and set to the rear of the main aeroplane at a distance less than the depth of said aeroplane, and a supplementary aeroplane of less width than the auxiliary aeroplane, spaced from said auxiliary aeroplane and at a level intermediate between those of the main and auxiliary aeroplanes, substantially as described.

3. An air ship, having a propeller, a vertical vane in the upper portion of the air ship, a vertical shaft to which said vane is secured, an arm extending rearwardly from said shaft and a weight secured to the free end of said arm, substantially as described.

4. An air ship having a propeller, a vertical vane in the upper portion of the air ship, a vertical shaft to which said vane is secured, an arm extending rearwardly and 5 downwardly from said shaft and a weight secured to the free end of said arm, substantially as described.

In testimony whereof we have hereunto

set our hands in the presence of two subscribing witnesses.
